The ornamental design for a prefabricated house as shown and described.

DESCRIPTION

1. Prefabricated House

1.1 : Perspective

1.2 : Front

1.3 : Back

1.4 : Left

1.5 : Right

1.6 : Top

This design is for a prefabricated house which is easy to install and manage; the fine lines are just for expressing a transparent material, not the one showing the configuration; a bottom view has been omitted since the weight of the claimed design is heavy. The broken lines depict portions of the prefabricated house that form no part of the claimed design.
